SIGNAL RECEIVING AND REPRODUCING
SYSTEM

Robert M. Sprague, Hicksville, N. Y., assignor to
Press Wireless, Inc., Chicago, Ill., a corporation
of Delaware

Original application October 27, 1939, Serial No.
301,563. Divided and this application Septem-
ber 26, 1942, Serial No. 459,759

13 Claims. (Cl. 250—20)

This invention relates to wave signalling systems and more especially to systems of carrier wave transmission wherein the effects of parasitics, noise, harmonic distortion fading and undesirable level variations are to be avoided.

A principal object of the invention relates to a system for transmitting signals whether oral, visual or control, through the intermediary of a transmission link, for example a high-frequency channel or radio channel, wherein the signal reproduction is rendered substantially independent of undesirable level changes.

Another principal object is to provide an improved radio signalling system which is singularly free from the effects of fading, echo, harmonic distortion, parasitic noises and the like.

A further object is to provide an improved manner of receiving message signals through the intermediary of a frequency modulated subcarrier.

A further feature relates to a receiver or reproducer of facsimile signals and the like, employing a specially designed band-pass filter for eliminating harmonic distortion in the transmitting medium or link and also for eliminating noise components below the actual frequency spectrum employed for signalling.

A further feature relates to a facsimile receiver or the like for use in a frequency modulation system and having an automatic level control determined by the received side-bands as distinguished from the carrier.

A further feature relates to a receiver for frequency modulation systems employing the combination of a specially designed filter and power limiter whereby all undesirable level variations which are not fully compensated for by the automatic volume control are ironed out in order to supply an undistorted signal of unvarying level to succeeding circuits in the receiver.

A further feature relates to a frequency de-modulator or converter arrangement for a receiver operated by a received frequency modulated wave, whereby the frequency modulations are converted to amplitude variations with a linear ratio between the frequency and amplitude and with a high ratio of signal-to-noise.

A still further feature relates to an improved facsimile receiving system whereby improved picture definition is obtained at higher transmission speeds and wherein the ratio of signal-to-noise is high and the susceptibility to selective fading is decreased.

Other features and advantages not specifically enumerated will be apparent after a consid-

eration of the following detailed descriptions and the appended claims.

While the invention will be illustrated in connection with facsimile transmitting and receiving systems, it will be understood that this is merely for explanatory purposes and that various features and aspects of the invention can be employed in other kinds of signalling or control systems. Accordingly in the drawings,

10 Figs. 1 and 2 are a schematic wiring diagram of a receiving system according to the invention.

Fig. 3 is an enlarged diagram of part of the converter unit of Fig. 2.

15 Figs. 4 and 5 are respective modifications of the converter section illustrated in Fig. 3.

In the drawings (Fig. 1), the block T represents a transmitting source of the type described in application Serial No. 301,563, filed October 27, 1939, (Patent No. 2,299,937, granted October 27, 1942) whereby the original signals e. g. lights and shades of picture or the like are converted into a subcarrier of audio frequency which carrier is frequency modulated in accordance with the picture ranges or the like. In accordance

20 with said application, the spectrum of the frequency modulations is so arranged that the uppermost frequency e. g. 3000 C. P. S. is less than the second harmonic of the lowermost frequency e. g. 1800 C. P. S. the limits of said spectrum representing certain extreme shades of the picture or other subject matter being transmitted. This spectrum-limited frequency modulated subcarrier is then transmitted over any wire line or over a radio channel by conventional amplitude modulation arrangements.

25 The transmitted signal from source T, e. g. in the form of an amplitude modulated radio carrier wave, is applied to any well-known form of radio receiver represented by the block RR, wherein the modulations of from 1800 to 3000 cycles are detected or demodulated. These demodulated signals are then applied to the resistor pad comprising resistor elements 201 to 205 inclusive and thence through the band-pass filter

30 206. Filter 206 eliminates all harmonics of the signal frequencies of the 1800-3000 cycle band that may have appeared as a result of "selective fading" or other causes during transmission, and the said filter passes only the signal as actually

35 passed by the corresponding filter at the transmitter. Filter 206 also eliminates any "noise" voltage outside its band-pass. Since there may be side-band frequencies present because of the variation of the carrier during transmission, the lower cutoff frequency of filter 206 must not be

chosen too close to the lower end of the actual signal band, that is, too close to 1800 C. P. S. nor to the upper limit of this band, that is, 3000 C. P. S. Preferably, the lower cutoff of filter 206 is spaced from the lower limit of the signal band the same distance as the spacing between the upper cutoff of filter 206 and the upper limit of the signal frequency band. Thus the pass-band is symmetrical and is sufficient to pass all desired side-band frequencies. The filter used in practice passes between 1500 and 3300 cycles.

The signal from filter 206 may vary in amplitude and must therefore be ironed out to a uniform level. This is effected by the A. V. C. circuit of amplifier tubes 236 and 251 and by the power limiter tube 271. Tube 217 is a straight amplifier tube preferably of the double triode type having two separate output circuits, one of these output circuits including plate 217a and cathode 217b leads to the monitoring meter 226 and monitoring jack 345, whereby the average level of the signal can be determined and adjusted by potentiometer 213. The other output circuit including plate 217c and cathode 217d feeds into amplifier tubes 236 and 251. Tubes 236 and 251 are preferably high gain pentodes having a remote cutoff. The D. C. plate supply for tube 217 is derived from a suitable A. C. source 342 over power transformer 333, full-wave rectifier 334, D. C. smoothing filter 335, 336, 337, conductor G, thence through the low frequency choke 290, conductor G1 and resistor 233 to plate 217c. Plate supply conductor G1 is also connected by way of resistors 227 and 222 to plate 217a the various resistors being provided with suitable by-pass condensers as shown. The signal developed across coupling resistor 229 is impressed through condenser 230 on the control-grid 236a of tube 236, the cathode 236b of which is connected to the suppressor-grid 236c. The plate 236d and screen-grid 236e are supplied with appropriate D. C. potentials from conductors G and G1. The output of tube 236 is fed to a similar amplifier pentode 251. The output of tube 251 is coupled through resistor 255 and condenser 256 to the connected control grids 264a, 264b of the double triode tube 264. The signal current in the circuit of plate 264c is applied to the rectifier tube 252 and this rectified signal voltage is filtered and smoothed by the resistance-condenser filter 248, 249, 250. The rectified voltage is then applied over A. V. C. conductor H through resistors 247 and 235 to the respective control grids of tubes 251 and 236. Thus when a drop in level occurs, the voltage rectified by tube 252 decreases, with a similar decrease in negative grid bias of tubes 236 and 251 and the gain is thereby increased to bring the voltage back approximately to its former magnitude. In this A. V. C. arrangement, the A. V. C. signal is therefore controlled not by the level of the received radio carrier voltage but by the demodulated signal voltage. Thus, even though the carrier remains constant and the side-band signals fade, the demodulated signal will remain constant.

The other plate circuit of tube 264 feeds the power limiter tube 271. Tube 271 performs several functions. First the action of the A. V. C. circuit above described is not instantaneous because of the resistance-capacity filter and therefore on a sudden fade of the received radio signal, the latter will drop for a short period. Secondly, the A. V. C. is not perfect and should the signal fade to the order of 30 db., the A. V. C. will hold the fade down to only 3 or 4 db. I have found

that this level variation is still too great for the best results in facsimile or picture transmission. Tube 271 takes care of both these conditions by amplifying the signal impressed thereon by transformer 269 up to a predetermined value and then as the signal increases further the output remains constant over a very wide range. The tube 271 is preferably connected in balanced or push-pull relation to the secondary winding of transformer 269, and the control-grids 271a, 271b are at zero bias with respect to the associated cathodes 271c, 271d. Consequently, as the grids swing positively, grid current flows through the resistance 270. This automatically applies a bias to the tube 271 which bias builds up substantially in proportion to the input voltage, thus holding the output substantially constant. Preferably, a resistance 273 is provided in the common plate lead to make the characteristics of the tube 271 linear up to a certain point and then to cause it suddenly to flatten out. This is probably due to the fact that as the grid voltage increases positively, the bias built up in resistor 270 does not increase by quite the same amount, but resistor 273 serves to lower the plate voltage as the plate current increases. The output of tube 271 is a substantially square wave wherein substantially only odd harmonics are present as a result of the balanced or push-pull connection. These odd harmonics must be eliminated before passing the signal to the converter circuit, the elimination being effected by filter 274 which is a low-pass or preferably a band-pass filter, the lower cutoff portion eliminating any noise introduced at any preceding point in the circuit. Filter 274 may be identical to filter 206.

The converter

The signal is then applied to the converter circuit wherein the frequency changes in the signal are converted to amplitude changes. The control elements of this converter consist of resistor 281, condenser 282 and inductance 283 connected to the plate circuit of amplifier tube 276. The condenser 282 and inductance 283 are designed so as to be "series resonant" at some frequency below the lowest signal frequency, which has been assumed to be 1800 cycles. In order to make the resultant voltage applied to the control grid of amplifier tube 287 linear, with respect to frequency, the impedance of condenser 282-inductance 283 combination must be low compared to resistance 281 even at the highest frequency passed. The series resonant frequency of 282 and 283 is placed at the lower frequency attenuation peak of band-pass filter 274, for example at approximately 1380 C. P. S. This is done because at frequencies less than the said series resonant frequencies, the voltage will again increase and will reach a maximum at very low frequencies, with the result that any noise being received at frequencies less than the said resonance frequency will be transmitted at greater amplitude than the frequency adjacent the resonant frequency of the 282, 283 combination. Consequently, it is necessary to place the resonance frequency at some value at which all noise has been filtered out. Of course, the nearer the said resonance frequency is to the lowest signal frequency being transmitted e. g. 1800 C. P. S., the greater will be the change of voltage with change of frequency, thus giving a better response ratio of signal-to-noise. Another resistor 284 is provided having about one-tenth of the value of resistor 281 and it serves to prevent low frequency

noise that the filter 274 may not have completely eliminated, from rising to too great a value. This resistor 284 must also be high compared to the maximum impedance of 282—283, otherwise an undesirable phase shift will result.

The converted signal is then applied to an amplifier tube 287 which may be of any suitable type preferably a type 6C8 upon whose main control grid 287a the converted signal is impressed. The output of tube 287 is further coupled in balanced relation to another amplifier stage comprising tubes 301 and 302 connected in push-pull relation whereby the signal level is raised to the desired value. It will be understood of course that any well-known linear amplifier may be used for amplifying the converted signal.

The amplified output of tubes 301, 302, is then rectified in a suitable rectifier 224 and the rectified output is passed through a low-pass filter 304. This filter attenuates all frequencies above the lowest transmission frequency e. g. 1800 C. P. S. leaving only the demodulated varying amplitude signal corresponding to the original photoelectric cell signal as delivered at the machine facsimile at source T. The variable amplitude signal from filter 304 can be applied directly to any well-known picture reproducing machine. However, in the event that the machine R is of a type which is operated on a modulated audio frequency, for example an 1800 cycle tone, the signal from filter 304 is used to modulate a locally generated 1800 cycle source. For this purpose, there is an oscillator tube 307 which is provided with circuit connections 308, 309, 310, 311, whereby a sustained 1800 cycle tone is generated. This 1800 cycle tone or current is then impressed in balanced relation on the control-grids 318a, 318b of a modulator tube 318. The plates 318c, 318d, are supplied with plate potential from the output of filter 304 which is connected in balanced relation to the primary of coupling transformer 320. As a result, there is impressed upon the balanced amplifier tube 322, an 1800 cycle current modulated in accordance with the signals from filter 304. If desired, the output of the amplifier of tube 322 may be passed through a filter 326 having a band-pass width suitable for passing the 1800 cycle wave with the necessary side-bands. The modulated 1800 cycle signal may then be passed through a suitable resistor pad 327 to 331 and thence to the facsimile reproducing machine R. It will be understood of course that the facsimile transmitting machine at source T and the facsimile reproducing machine R are synchronized by any method well-known in the facsimile art.

In order that the proper range of tone values may be employed at the receiver RR, means are provided for obtaining zero output of the locally generated 1800 cycle carrier from tube 307 to correspond with zero voltage on the control-grid of the frequency modulator tube at the transmitter. This is accomplished by applying a fixed negative bias on the plates 318c, 318d of the modulator tube 318 as indicated schematically by the bias source 350. By means of the potentiometer 275, the gain of tubes 276, 287, 301 and 302, are then increased until the voltage developed across resistor 305 is equal to the negative bias from the source 350. Thus, a net voltage of zero is applied to the plates of tube 318 which is the threshold point or zero voltage point. Under the above assumption of a minimum signal frequency of 1800 cycles, this zero voltage corresponds therefore to this lower signal fre-

quency, consequently any change in the frequency applied to tube 276 will give a corresponding 1800 cycle output from the modulator 318.

In adjusting the receiver, the average input is 5 adjusted to normal by the meter 226 and the level of the received signal is increased by potentiometer 275 until the voltmeter 306 reads zero, thus placing the balanced modulator 318 on the threshold of operation.

10 The apparatus at the transmitter having been adjusted as described in said U. S. Patent No. 2,299,937 so as to provide the requisite frequency shift of 1200 C. P. S. i. e. from 1800 to 3000 C. P. S. for the range of tone values to be transmitted, this change of frequency will cause at the receiver 15 a voltage to be impressed on the plate of tube 318 resulting in a certain level of the local 1800 cycle oscillations applied to tube 322. This level is adjusted to normal by increasing the gain by 20 means of potentiometer 321. After these preliminary adjustments at the transmitter and receiver, the entire system is in readiness for the transmission of the subject matter which may be a picture, written matter or any visual display 25 consisting of variations of tone or shade values.

While in the foregoing description reference has been made to the transmission of a picture by means of frequency modulations between 1800 C. P. S. and 3000 C. P. S., it will be understood 30 that the invention is not necessarily limited thereto. However, I have found from actual tests and demonstrations that the above shift of from 1800 to 3000 C. P. S. is more than sufficient to transmit all the frequencies present in modern 35 picture or facsimile transmitters. On the other hand, I have transmitted with good results with the equipment described, using a frequency shift of from 1200 to 1800 cycles. Furthermore, while particular apparatus and parts have been described, it will be understood that variations may 40 be made therein as will be obvious to those skilled in the art and without departing from the spirit and scope of the invention. With the equipment as described, I have succeeded in passing linearly, 45 frequencies up to 1400 cycles with no apparent attenuation at the upper frequencies and furthermore I have transmitted articulate speech and music through the equipment merely by replacing the facsimile transmitter at source T by a voice frequency generator and by replacing the 50 reproducer R by a voice frequency reproducer. With a higher range of frequencies such as between 5000 and 7500 C. P. S., or even 5000 and 6500 C. P. S., frequencies up to 4500 C. P. S. can 55 be passed. The invention is not limited to facsimile transmission or to ordinary voice frequency telephony. The system is well suited for secret 60 radio transmission because the original voice signals that may be received from source T are radiated from the radio transmitter in an unintelligible form, and in order that they may be reproduced, a receiver such as shown in the drawings and adjusted and correlated with the transmitter T, must be employed. I have also found 65 that a system as described when used in facsimile or voice communication eliminates to a substantial extent, well-known echo effects. As a result of using the system as disclosed, the following among other results have been obtained.

70 1. The elimination of all harmonic distortion by using the various low-pass and band-pass filters such as 206 and 274 and the elimination of all noise below the actual frequency range used for signalling.

75 2. The automatic volume control is rendered

more effective by being controlled by the demodulated signal in tube 251 giving constant amplitude to the converted signal applied to tube 216.

3. The supplementing of the automatic volume control by the limiter tube 271 and filter 274 whereby all changes in level which escape the automatic volume control circuit are ironed out, thus supplying an undistorted signal at perfectly constant level to the succeeding circuit.

4. The provision of a converter circuit associated with tube 216 whereby frequency changes are made to amplitude changes with perfect linearity and with high ratio of signal-to-noise.

It will be understood of course that while one particular form of level control has been disclosed in connection with the tubes 236 and 251, any other well-known form may be employed and in addition if desired, another A. V. C. signal may be derived from the radio carrier and if desired, the receiver RR may be of the diversity type. The A. V. C. voltage derived as shown may be applied to control the gain of the receiver itself, being applied to all controlled tubes in the receiver, or to some of them, leaving the radio-carrier-derived A. V. C. on the others.

Instead of employing a series condenser-inductance combination 282, 283 (such as shown in Fig. 2 and in the corresponding enlarged view of Fig. 3) for inverting the frequency modulations to amplitude variations, an arrangement such as shown in Fig. 4 may be employed wherein the parts corresponding to those of Figs. 2 and 3 bear the same numerals. In this modification, the condenser 279 is designed to be of high impedance compared to resistance 284. The voltages developed across resistance 284 as a result of the frequencies impressed on tube 276, are used to control the amplitude in the output of tube 287. Instead of using a series resistance-condenser, a series resistance-inductance combination may be employed, this modification being shown in Fig. 5 wherein the impedance of inductance 283 is low compared to resistance 281. While the embodiment of Figs. 4 and 5 each give zero voltage at zero frequency when operating between 1800 and 3000 C. P. S., only approximately 67 percent voltage change is produced; whereas with the series resonant circuit 282, 283 of Fig. 2, when this combination is resonant at 1400 C. P. S., over the same frequency range of 1800 to 3000 C. P. S., there is obtained a 300 percent voltage change. Various changes and modifications may be made in the disclosure without departing from the spirit and scope of the invention. Thus, if under certain conditions of operation, for example at very high speeds of transmission, undesirable phase shifts occur in the various filters described, these phase shifts may be compensated for by connecting in circuit with one or more of the filters suitable phase equalizers. However, it has been found that at ordinary commercial transmission speeds, such equalizers are not necessary.

This application is a division of application Serial No. 301,563, filed October 27, 1939, issued as U. S. Patent No. 2,299,937, granted October 27, 1942.

What I claim is:

1. A receiver for receiving a frequency modulated subcarrier transmitted as an amplitude modulated main carrier and wherein the frequency spectrum of the subcarrier band is limited so that the uppermost frequency is less than twice the frequency of the lowermost frequency, said receiver comprising means to detect the sub-

carrier modulations from said main carrier, a band-pass filter for passing said spectrum while eliminating any harmonics of the spectrum frequencies which may have been introduced during transmission, means to convert the frequency band passed by said filter into corresponding amplitude variations, and a signal reproducer operated under control of said amplitude variations.

10 2. A receiver according to claim 1 in which said frequency spectrum as passed by said filter is confined to the audio frequency band.

15 3. A receiver according to claim 1 in which a grid-controlled vacuum tube amplifier is provided for amplifying the detected subcarrier signals passed by said filter, and an automatic volume control circuit is provided for said vacuum tube amplifier said circuit applying a gain control voltage to said amplifier which is determined by the level of said detected subcarrier.

20 4. A receiver according to claim 1 in which a grid-controlled amplifier is provided for amplifying the detected subcarrier signals passed by said filter, an automatic volume control circuit is provided for said amplifier for applying a gain control voltage to the amplifier which is determined by the level of said detected subcarrier, and a power limiter tube is provided for reducing the effect of the level variations to a value less than that obtained by said automatic volume control circuit, and another band-pass filter upon which the output of the power limiter is impressed, said other filter having substantially the same band-pass as said first-mentioned filter.

25 30 5. A receiver according to claim 1 in which said converter means includes a network which is series resonant at a frequency below the lower limit of said spectrum.

35 6. A receiver according to claim 1 in which said converter means includes a network comprising a resistance, capacitance and inductance, the series resonance of the condenser and inductance combination being at a point below the lower limit of said spectrum, and the impedance of the condenser-inductance combination being sufficiently low compared with said resistance so that the resultant voltage amplitude from the converter is linear with respect to frequency.

40 7. A receiver according to claim 1 in which a rectifier is provided for rectifying the signals from said converter means and a filter is provided upon which the rectified signals are impressed, said filter substantially attenuating all frequency components below the lower limit of said spectrum.

45 8. A signal receiver for use in frequency-modulated signal systems, comprising a detector for detecting said frequency modulations in a predetermined audio frequency signal band, a band-pass filter for suppressing most frequencies below the lowest detected frequency corresponding to the original signals and for suppressing frequencies of any harmonics of any frequency in said predetermined band, means to convert said detected frequencies into waves of substantially uniform amplitude, and means to reconvert said uniform amplitude waves into other corresponding varying amplitude waves.

50 9. A frequency demodulator for converting frequency modulations into corresponding amplitude modulations confined to a predetermined band comprising a grid-controlled vacuum tube, a signal input circuit connected to the control grid of said tube and on which the frequency modulations are impressed, said tube having an output

circuit comprising a network having a resonant section which has a series resonance at a frequency below the lowest of the frequency modulations impressed on said input circuit.

10. A frequency demodulator according to claim 9 in which a band filter is connected to said input circuit to limit the frequency band applied to said demodulator, and said resonant section has a series resonance below but relatively close to the lowest of the impressed frequency modulations, and to said lower attenuation peak of said filter.

11. A frequency demodulator according to claim 9 in which said network comprises in series a resistance, a condenser and an inductance, the combined impedance of the condenser and the inductance at the highest frequency of said impressed signal frequency modulations being substantially less than said resistance.

12. A frequency demodulator according to claim 9 in which said network includes in series a resistance and a resonant section, and another resistance is connected in shunt to said resonant section, said other resistance having approximately one-tenth the value of the first-mentioned

resistance, and being high compared to the combined impedance of said condenser and inductance at the highest frequency of said impressed signal frequency modulations.

13. A signal receiving system for receiving a frequency-modulated carrier wherein the frequency spectrum of the modulation signals has a frequency range within the same frequency range as the frequency range of the original signals to be transmitted, detector means to detect said modulation frequencies, a network upon which the detected modulation frequencies are impressed for eliminating all harmonics of said spectrum frequencies which harmonics may have been undesirably introduced in the transmission channel to which the receiving system is connected, means to convert said modulation frequencies from said network into corresponding amplitude modulations, a separate local source of oscillations, means to apply said amplitude modulations to said local source, and a signal reproducing device controlled by the output of said modulated local source of oscillations.

ROBERT M. SPRAGUE.
